UNITED STATES PATENT OFFICE.

JOHN A. HEBB, OF UNIONTOWN, PENNSYLVANIA, ASSIGNOR TO THE HEBB COKE DRAWER CO., OF UNIONTOWN, PENNSYLVANIA.

COKE-DRAWING MACHINE.

SPECIFICATION forming part of Letters Patent No. 728,102, dated May 12, 1903.

Application filed August 14, 1902. Serial No. 119,619. (No model.)

To all whom it may concern:

Be it known that I, JOHN A. HEBB, a citizen of the United States, residing at Uniontown, in the county of Fayette and State of Pennsylvania, have invented certain new and useful Improvements in Coke-Drawing Machines, of which the following is a specification, reference being had therein to the accompanying drawings, forming part of this specification.

Figure 1 is a plan view of my improved coke-drawing machine, showing it in position in front of an oven-door, portions of the conveying mechanism being broken away. Fig. 2 is a vertical longitudinal sectional view on the line II II of Fig. 1. Fig. 3 is a similar view at right angles to Fig. 2 indicated by the line III III of Fig. 1. Fig. 4 is a detail view of the vertical clutch mechanism of Fig. 3 and its operating-lever at right angles to the other figure. Fig. 5 is a vertical sectional view on the line V V of Fig. 2 looking in direction of the arrow.

My invention relates to apparatus for drawing coke from the oven, wherein a traveling structure is provided with a reciprocating beam having a rake-head adapted to be extended into and withdrawn from the oven to empty the contents therefrom.

The present application refers more particularly to the means for raising and lowering the operative end of the rake-beam.

Related subject-matter is embodied in separate applications bearing the Serial Nos. 119,617, 119,618, 119,620, 120,559, and 125,644.

Referring now to the drawings, A represents the framework of a portable carriage carrying the turn-table B, upon which are mounted the various manipulative portions of the machine. Mounted in suitable bearings is a main shaft 4, driven at one end by a suitable prime mover, as a steam-engine or electric motor. Centrally mounted in step-box 6 is a vertical shaft 7 in driving engagement with the shaft 4 by bevel-gears 9 10, by which shaft 7 is continuously driven. The beam-supporting and beam-manipulating (longitudinally) framework and mechanism is mounted on the two main standards 22 22 at each side of the central shaft 7, which standards are secured to the upper side of the

turn-table and are provided at their upper portions with pillow-blocks or bearings 23, in which is mounted the cross-shaft 24, provided at its middle portion centrally above the center of the machine with driving-pinions 25 in driving engagement with racks 26, secured to beam 27, the center web of which extends between pinions 25 and rests upon a roller 28, journaled on shaft 24, by which the weight 60 of the beam is carried and the teeth relieved from the strain of gravity.

On each side of the beam, freely journaled on shaft 24, are the conical friction-drums 36, provided on their inner portion with peripheral bevel-teeth 37, the teeth on both of such drums being in constant engagement with a driving bevel gear-wheel 38, secured to the upper end of shaft 7, by which both friction-drums are constantly driven in opposite directions. Beyond the friction-drums at each side is a surrounding friction-sleeve 40, each of which is provided with a hub portion in driving engagement with the shaft 24 by spline or key 41, so that when either of such sleeves is brought into frictional engagement with the drum by shifting it upon the shaft it will transmit movement to the shaft 24 in one direction or the other, according to which drum is utilized, and thereby through pinions 25 and rack 26 will impart forward or back movement to the beam.

The shifting operation is secured through lever 42, pivoted at 43 and connected at 44 to a shifting bar 45, mounted in suitable bearings on uprights 22 and provided with forks 46, engaging collars or flanges on the hubs of sleeves 40.

The forward end of the beam is provided with a pivotally-attached rake-head 31, adapted to fold backwardly when coming into contact with the coke on entering the oven and to be automatically extended by tension of a spring 32 at the back end of the beam and connected to the rake by rod 33 and arms 35.

The inner end of the beam is raised and lowered by the rotation of shaft 47, the inner end of which is provided with a bevel-gear 48 in mesh with the upper and lower driving-bevels 49 and 50, loosely mounted on shaft 7 and provided on their inner portions with clutches 51, with which is adapted to engage

a vertically-moving clutch 52 in key or spline engagement with the constantly-running shaft 7.

The clutch 52 engages with clutch of bevel 5 49 or 50 and is raised or lowered by lever 53 engaging in a groove in the clutch, the lever being secured to shaft 54, mounted in bearings in the framework and provided with an operating hand-lever 55, extending upwardly 10 and within easy range of the operator.

For the purpose of maintaining the lever 53 and clutch 52 in their normal middle inoperative position shaft 54 is provided with a short arm 56, upon the outer end of which is 15 hung a counterweight 57 by slot 58, elongated downwardly below the end of the arm.

The counterweight slightly overbalances the lever 53 and the suspended clutch 52 and rests on the turn-table, as shown. When the 20 clutch is thrown down, the weight 57 is raised from its bearing, and when the clutch is thrown up the arm 56 passes freely down through slot 58, the clutch 52 tending to make its fall by gravity to the normal middle position illustrated.

Shaft 47 is mounted in suitable bearings, as shown, and provided with an outer worm-wheel 59, engaging with a similarly-toothed segment 60, pivoted in a bearing-frame 61, 30 and provided with an extended lever-arm 62. Upward or downward movement of the inner end of the beam is imparted to it by arms 63, pivoted to lever-arm 62, carrying an under roller 65, upon which the beam rests, and by 35 supplemental links 64 an upper roller 66. Links 67, pivoted at 68 in upwardly-extending guiding-extensions 69, maintain arms 63 and the supporting-roller 65 in an erect position during the raising and lowering movements 40 of the beam. By this mechanism the beam is capable of being raised or lowered or held in any position, and positive downward pressure may be exerted upon it to force the rake into the coke to facilitate its entrance during the 45 rapid reciprocating movements imparted to the beam and rake by quickly alternating the engagement of the clutches 40, already described. The beam-supporting framework just described is located between the pivotal 50 support of the beam and its outer end, thus placing the support as nearly as possible to the rake-head, where it may exert the greatest leverage. By this same mechanism—to wit, pinions 25 and rack 26—the beam is 55 thrust into or withdrawn from the oven, and such movements may be accomplished while the rake-head is being raised or lowered when the rake is not in engagement with the coke, the operation being simultaneously performed with lever 42 in the left hand for operating the clutch-sleeves 40 and lever 55 in the right hand.

The operation of raising and lowering the beam will be readily understood from the 60 foregoing description. It will also be understood that changes and variations may be made in the specific details by the skilled

mechanic without departing from the invention, and all such are contemplated as within the scope of the following claims.

70

What I claim is—

1. In a coke-drawing machine, mechanism for raising and lowering the beam, consisting of a crank, arms connected therewith and provided with means for engagement with 75 the beam, a shaft, and gearing for imparting movement to the crank-arm and beam in either direction, substantially as set forth.

2. In a coke-drawing machine, mechanism for raising and lowering the beam consisting 80 of a supporting-framework adapted to engage the upper and under side of the beam respectively, a crank-arm connected with said framework, and an operating-shaft in driving connection with said crank-arm, with means for 85 driving the shaft and crank-arm in either direction, substantially as set forth.

3. In a coke-drawing machine, mechanism for raising and lowering the beam consisting 90 of a supporting-framework adapted to engage the upper and under side of the beam respectively, a crank-arm connected with said framework and provided with worm-gearing, an operating-shaft provided with a worm-wheel in engagement therewith, and means for 95 rotating the shaft in either direction, substantially as set forth.

4. In a coke-drawing machine, mechanism for raising and lowering the beam consisting 100 of a supporting-framework adapted to engage the upper and under side of the beam respectively, a crank-arm connected with said framework and provided with worm-gearing, an operating-shaft provided with a worm-wheel in engagement therewith and provided with 105 a bevel-wheel, a rotating shaft, bevels loosely mounted thereon and in engagement with said bevel, and means for connecting either of said bevels with said rotating shaft, substantially as set forth.

5. In a coke-drawing machine, mechanism for raising and lowering the beam consisting 110 of a supporting-framework adapted to engage the upper and under side of the beam respectively, a crank-arm connected with said framework and provided with worm-gearing, an operating-shaft provided with a worm-wheel in engagement therewith and having a bevel-wheel, a rotating shaft, bevels loosely mounted 115 thereon in engagement with said bevel, and provided with clutch devices on their inner faces, a clutch in spline engagement with the rotating shaft, and means for shifting the clutch, substantially as set forth.

6. In a coke-drawing machine, mechanism 125 for raising and lowering the beam consisting of a supporting-framework adapted to engage the upper and under side of the beam respectively, a crank-arm connected with said framework and provided with worm-gearing, 130 an operating-shaft provided with a worm-wheel in engagement therewith, a rotating shaft, bevels mounted thereon, in engagement with said bevels and provided with

clutch devices on their inner faces, a clutch in spline engagement with the constantly-rotating shaft, means for shifting the clutch, and means for holding the clutch normally out of engagement, substantially as set forth.

7. In a coke-drawing machine, mechanism for raising and lowering the beam consisting of a vertically-movable framework, provided with rollers adapted to engage the upper and under side of the beam respectively, a crank-arm adapted to raise and lower said framework and provided with worm-gearing, a shaft provided with a worm-wheel in engagement with the said gearing, and means for driving said shaft in either direction, substantially as set forth.

8. The combination with a reciprocating beam and a vertical guiding-frame therefor; of raising and lowering mechanism consisting of a framework provided with rollers adapted to engage the upper and under sides of the beam, a pivoted crank-arm connected with said frame and adapted to raise or lower it, and means for operating the crank-arm in either direction.

9. The combination with a reciprocating beam and a vertical guiding-frame therefor; of raising and lowering mechanism consisting of a framework provided with rollers adapted to engage the upper and undersides of the beam, a crank-arm connected with said framework adapted to raise or lower it, means for operating the crank-arm in either

direction, and guiding-links connected with the guiding-framework and the raising and lowering framework respectively, substantially as set forth.

10. The combination, with a reciprocating rake-beam provided with a rake-head, and a pivotal support and reciprocating mechanism for the beam assembled at a common point: of mechanism for raising and lowering the beam located between such pivotal support and the rake-head, substantially as set forth.

11. The combination with a reciprocating rake-beam provided with a rake-head, and a pivotal support and reciprocating mechanism for the beam assembled at a common point: of mechanism for raising and lowering the beam and for providing a stationary sliding support therefor at varying heights, located between such pivotal support and the rake-head, substantially as set forth.

12. The combination with a reciprocating rake-beam provided with a rake-head, and a pivotal support and reciprocating mechanism for the beam assembled at a common point: of mechanism for raising and lowering the beam and screw-gearing for actuating said mechanism, substantially as set forth.

In testimony whereof I affix my signature in presence of two witnesses.

JOHN A. HEBB.
